United States Patent Office

Des. 218,362
Patented Aug. 11, 1970

218,362

BASE FOR A TURNTABLE

Herbert N. Hartman, New York, N.Y., assignor to British Industries Corp., Westbury, N.Y., a corporation of New York

Filed June 13, 1968, Ser. No. 12,344

Term of patent 14 years

Int. Cl. D14—01

U.S. Cl. D56—4

The single figure is a perspective view of a base for a turntable showing my new design.

The opposite side is a mirror image of the side shown and the back is substantially flat and unornamented.

I claim:

The ornamental design for a base for a turntable, substantially as shown and described.
